GOLF PUTTER

Ralph Cefaly, 3905 Perry St., Brentwood, Md.

Filed Sept. 4, 1964, Ser. No. 81,595

Term of patent 14 years

(Cl. D34—5)

FIGURE 1 is a front elevational view of a golf putter showing my new design.

FIGURE 2 is a rear elevational view of the putter in FIGURE 1;

FIGURE 3 is a top plan view of the putter in FIGURE 1;

FIGURE 4 is a bottom plan view of the putter shown in FIGURE 2; and

FIGURE 5 is a side elevation viewed from the left of the putter in FIGURE 1.

The dominant features of the design reside in the portions shown in full line.

The upper portion of the shaft is conventional and has been omitted for convenience of illustration.

I claim:

The ornamental design for a golf putter, as shown and described.
